UNITED STATES PATENT OFFICE.

WILLIAM P. PIERCE, OF NEW YORK, N. Y.

IMPROVEMENT IN WEIGHING-SCALES.

Specification forming part of Letters Patent No. 96,955, dated November 16, 1869.

To all whom it may concern:

Be it known that I, WILLIAM P. PIERCE, of the city of New York, county and State of New York, have invented a new and useful Improvement in Scales; and I do hereby declare that the following is a full, clear, and exact description of the construction and operation of the same, reference being had to the annexed drawings, making a part of this specification.

In the usual construction of the beams of scales the fulcrum of the beam is a steel edge, and the supports of the articles to be weighed and of the weights are steel edges.

My improvement consists in making the steel bearing-points the eccentric ends of steel screws, for the purpose of providing great facility of nice adjustment of points.

Figures 1 and 2 are views of the beam and the parts referred to, the same letters applying in both figures.

A is the beam.

B is the standard.

E E are the dishes.

a a are the fulcrum-points.

b b are the supporting-points at end of beam. The fulcrum-points and the supporting-points are most readily provided by being at end of steel screws, and great nicety of adjustment of the distances between the fulcrum-points and supporting-points is provided by making the supporting-point at the end of the screw a little eccentric to the axis of screw.

Fig. 3 is a magnified section of screw, in order to show eccentricity of point of screw.

c c are conical bearings, attached to the under side of the dishes E E.

d d are balance-weights, so attached to the dish that when the balance-weight hangs vertical the dish is horizontal.

e e are connecting-pieces, of shape shown in drawings, which are fastened to dish at m, and into which the rod carrying the balance-weight d d is screwed at n.

g g are parts of the standard B, one at each end, to receive the balance-weight, and are of conical or hemispherical form, as shown in drawings. Within this cone the balance-weights d d hang, each having only room enough to provide for the oscillation of the weight when the scale is being used.

The screws h h, by which the balance-weight rod is attached to the pieces e e, are of such length that, when screwed up properly, the dishes, the bearing-points, and the balance-weights, while they have all necessary freedom, cannot be entirely separated.

What I claim as invention, and desire to secure by Letters Patent, is—

1. The pan E, supported on the end of the balance-beam by means of a point formed on the end of a screw and slightly eccentric to the axis thereof, for the purpose of linear adjustment.

2. The open loop-piece e, to the lower arm of which the balance-weight is connected by a screw, h, adjustable to form a stop to prevent the disengagement of said loop from the balance-arm, all substantially in the manner and for the purpose herein set forth.

WILLIAM P. PIERCE.
